SUPPORTING STAND FOR AN ELECTRIC KNIFE

Richard S. Hart, Wheaton, Ill., assignor to Sunbeam Corporation, Chicago, Ill., a corporation of Illinois

Filed June 12, 1967, Ser. No. 7,438

Term of patent 14 years

(Cl. D44—29)

FIG. 1 is a perspective view of a supporting stand for an electric knife showing my new design, with a knife handle shown in broken lines for illustrative purposes only; FIG. 2 is an enlarged scale front elevational view; FIG. 3 is a right side elevational view; FIG. 4 is a top plan view thereof; FIG. 5 is a sectional view taken on line 5—5 of FIG. 2; and, FIG. 6 is a sectional view taken on line 6—6 of FIG. 2.

I claim:

The ornamental design for a supporting stand for an electric knife, as shown and described.
